BOTTLE CARRIER

Prentice J. Wood, Jonesboro, James B. Funkhouser, Doraville, and Alfred J. Rinehart, Atlanta, Ga., assignors to The Mead Corporation

Continuation of abandoned design application Ser. No. 14,313, Nov. 5, 1968. This application Mar. 12, 1970, Ser. No. 22,717

Term of patent 14 years

Int. Cl. D9—03

U.S. Cl. D9—176

FIG. 1

FIG. 2

FIG. 3

FIG. 1 is an isometric view of a bottle carrier showing our new design;

FIG. 2 is a side elevational view showing the side opposite that seen in FIG. 1; and

FIG. 3 is an end elevational view thereof.

This is a continuation of our co-pending application Ser. No. D. 14,313, filed Nov. 5, 1968 and now abandoned.

The broken lines represent perforations.

We claim:

The ornamental design for a bottle carrier, as shown and described.
